UNITED STATES PATENT OFFICE

2,025,046

APPARATUS FOR DAMPENING THE PLATE
CYLINDERS OF LITHOGRAPHIC AND
ANALOGOUS PRESSES

John G. Goedike, San Antonio, Tex.

Application April 16, 1931, Serial No. 530,584

8 Claims. (Cl. 101—147)

(Granted under the act of March 3, 1883, as
amended April 30, 1928; 370 O. G. 757)

This invention described herein may be manufactured and used by or for the Government for governmental purposes, without the payment to me of any royalty thereon.

5 This invention relates to means for dampening the plates employed on lithographic presses for use in off-set lithographic and analogous printing operations and has for its primary object the provisions of a method and apparatus 10 whereby a lithographic plate containing the design to be printed is dampened by a process of condensation of moisture which is induced by the chilling of the lithographic plate cylinder on which the lithographic plate is mounted, the 15 plate cylinder being chilled by means of a cooling element which forms the low pressure or cooling side of a refrigerating system, and the amount of moisture condensed on the plates being controlled by the temperatures to which the 20 plate cylinders are lowered.

Another object of my invention is to provide a cooling element or coil which forms the low pressure or cooling side of a refrigerating system that is adapted to be positioned within the plate 25 cylinders of lithographic presses to chill the same in order to induce condensation of moisture on the external surface of a lithographic plate mounted thereon for damping the plate.

30 Another object of my invention is to provide a leak-proof plate cylinder for lithographic and analogous printing presses which is adapted to contain a refrigerating medium.

35 A further object of my invention is to provide a stuffing box and cap which permits the ready coupling or uncoupling of a refrigerating apparatus including a cooling element or vaporizer to one end of a plate cylinder or cylinders of lithographic presses for chilling the plate cylinders so as to cause the dampening of a lithographic plate 40 thereon by condensation of moisture from the air without interfering with the working parts on the other side of the press.

Hitherto the plates containing the design to be 45 printed which are mounted on the plate cylinders of lithographic and analogous presses have been dampened at each revolution of the press by a set of dampening rollers which are fed from a water fountain. These rollers consisting of hollow tube stock covered with several layers of 50 flannel with an outside covering of molleton or cotton material. In revolving against the surface of the plate these rollers have never touched the plates at all points with the result that dampening has been variable and unsatisfactory there- 55 by presenting the greatest problem to the litho-

graphic art. It was believed that a cold plate would not take ink and if a cold plate was employed that the design on the plate would pull the ink and string it out or further if the plate was warm the design on the plate would cause 5 the ink to scum and tint. The employment of the prior methods and apparatus for dampening lithographic plates entails a greater delay after the making of each print and requires more labor and are not as efficient as my method and apparatus for dampening the plates.

It is therefore the purpose of this invention to provide an apparatus which will avoid the disadvantages of the prior methods of dampening the plates used on lithographic and analogous 15 printing operations by the automatic condensation of moisture which result is obtained by the use of a cooling element or vaporizer which forms the low pressure or cooling side of a refrigerating unit that is adapted to chill or lower 20 the temperature of the plate cylinder used on lithographic or analogous printing operations close to the freezing point of water 32° F. for causing a condensation of moisture to be formed on the plate for dampening the same, thereby 25 eliminating the use of the present moistening devices such as dampening rollers fed from a water fountain, increasing the number of prints which may be produced in a given time, permitting the 30 producing of finer prints, making the operation 35 of producing the prints more efficient and economical, reducing the amount of labor required and the cost of making the prints and preventing the ink from being strung out, scum or tint.

35 My invention is based on the following principle. When air saturated with water in the form of elastic vapor is brought in contact with a colder substance, a part of the water so contained will be deposited on the surface of the 40 colder body in the liquid form, as dew. This takes place because any lowering of the temperature of air which is saturated lessens its capacity for watery vapor and results in the precipitation of the difference between the quantities it can take 45 up at the two temperatures. When the air is not saturated, moisture will still be deposited if the temperature of the colder body be at or below the "dew-point"—that is, cold enough to reduce the stratum of air in contact with it to a temperature just below that at which the amount 50 of water present is sufficient for saturation. The first case is well illustrated by the film of condensed moisture produced when we breathe upon a plate of glass or of polished metal, which is 55

colder than the saturated air issuing from the lungs; the second by the condensation of water as dew upon the glass and other objects out of doors when the same have been cooled to the dew-point by radiation. The well-known appearance of moisture upon the outside of a vessel of ice water when placed in a warm room is also a case of deposition from partly saturated air.

In order that my invention may be readily understood reference is had to the accompanying drawing in which corresponding parts are indicated by similar reference characters and in which:

Fig. 1 is a vertical sectional view of my improved dampening apparatus applied to the plate cylinder of a lithographic press;

Fig. 2 is an end view thereof with parts broken away, and

Fig. 3 is a cross sectional view taken on line 3-3 of Fig. 1 looking in the direction of the arrows.

In carrying out my invention the hollow plate cylinder 1 of a lithographic or analogous press is closed at each end by heads 2. The heads 2 of the plate cylinder 1 are provided with circumferentially arranged gear teeth 3 for rotating the plate cylinder 1, these gear teeth 3 being adapted to intermesh with other gearing of the press (not shown). The plate cylinder 1 is affixed to the heads 2 as stated above and said heads are rigidly mounted on shaft 4 to rotate therewith. Attached to the outside surface of plate cylinder 1 by any suitable means is a lithographic plate 5 containing the design to be printed. The ends 6 and 7 of the shaft 4 provide journals which are mounted in bearings 9 and 9' formed in the frame 10 of any suitable lithographic press. The end 6 of the shaft 4 is provided with a reduced end portion 11 forming a shoulder 12 and contains independent conduits or channels 13 and 14 which form portions of an intake and exhaust passage-way respectively. The intake channel 13 extends longitudinally from the outer end of the reduced end portion 11 through the central axis thereof to a point 15 on shaft 4 within the plate cylinder 1 where it extends radially to 16 of the outer surface 17 of shaft 4. The exhaust channel 14 extends longitudinally from the shoulder 12 formed by the reduced end portion 11 to a point 18 within the plate cylinder 1 where it also extends radially to 19 of the outside surface of the shaft 4.

Within the plate cylinder 1 and rotatable therewith is a distributing system comprising a tubular element 20 mounted closely adjacent the inner surface 21 of the plate cylinder 1 and provided with a clamping attachment 22 which is circumferentially arranged around the tubular element 20 for holding it in place. The ends 23 and 24 of the tubular element 20 are connected to the inner ends 16 and 19 of the intake and exhaust channels 13 and 14 respectively to form a leak-proof joint 25 by being welded thereto. The tubular element 20 forms the low pressure or cooling side of a closed refrigerating system for the purpose of chilling the plate cylinder 1 to cause a condensation of moisture to form on the exterior surface of the lithographic plate 5 for dampening thereof when in operation.

The high pressure side of the refrigerating system comprises a compressor 35, condenser 36, a liquid receiver 37 and expansion valve 38 which are connected to the device 20 of my invention by means of conduits 27 and 28. This connection is specifically made as follows. Adjacent the end

6 of the shaft 4 is a housing 29 which is attached to the outside frame 10 of the press by any suitable means such as bolts 30 and is joined to the external stationary conduit 27 which passes through the frame thereof for making a conducting passage between the conduit 27 and the internally rotary conduit 14, a similar connection being made between the external stationary intake conduit 28 and the internal rotary conduit 13 by means of a fluid tight joint formed in any suitable manner as by means of another housing in the form of a cap 31 which is secured in place by any suitable means such as bolts 32. Any suitable leak preventing means such as a resilient washer 33 may be inserted between the frame 10 and housing 29 as shown. A hole 34 may be provided for permitting the reduced end portion 11 of the shaft 4 to be lubricated.

In chilling the plate cylinder 1 for causing the dampening of the lithographic plate 5 attached thereto by the condensation of moisture thereon the compressor 35 forces the refrigerant under high pressure in a gaseous form into the condenser 36 which changes the gas into a liquid by giving up its heat to the medium about the condenser, the refrigerant flowing from the condenser 36 into the liquid receiver 37 from where it is conducted by the stationary intake conduit 28 through the expansion valve 38 then through the rotatable intake channel 13 provided in the end 6 of the shaft 4 from where it enters the end 23 of the rotatable tubular element 20.

The tubular element 20 constitutes the cooling element or vaporizer and forms the low pressure side of the refrigerating system. The refrigerant in the cooling element or vaporizer 20 is changed back into a gaseous form by the vaporizer absorbing the heat from the plate cylinder 1 which reduces the temperature thereof below the dew point of the atmosphere surrounding the plate cylinder to cause a condensation of moisture to form on the exterior surface of the lithographic plate 5 mounted thereon. The sole source of the condensed moisture on the plate is the atmosphere surrounding the plate.

The plate cylinder 1 when rotated by the gears 3 rotates the shaft 4 and the tubular element 20 attached thereto thereby keeping the metal plate cylinder 1 chilled at all points as near as practical below the dew point of the atmosphere to cause a condensation of moisture to form on the exterior surface of the lithographic plate 5 attached thereto thereby providing a dampened surface thereon. The refrigerant finally works its way through the end 24 of the rotatable tubular element 20 where it enters the inner end 19 of the rotatable exhaust channel 14 and leaves at the other end thereof emptying into the housing 29 to be discharged into the stationary exhaust conduit 27 which draws the refrigerant from the housing 29 creating a vacuum therein thereby causing the refrigerant to flow from the rotatable exhaust channel 14 into the housing 29 and be conducted back through the suction port 39 into the compressor 35 of the refrigerating system by means of the stationary conduit 27.

It will thus be seen that I have provided a highly novel, simple and efficient apparatus for dampening the plate cylinders of lithographic and analogous printing presses that is well adapted for all the purposes designated by any refrigerating system employing compression, vacuum, absorption or any other type and which will permit the use of any refrigerant such as

air, ammonia, methyl chloride, sulphur dioxide and various other refrigerants. Even though I have herein shown and described my apparatus for carrying out the invention as comprising certain structural elements it is nevertheless to be understood that changes may be made therein without departing from the spirit or scope of my invention.

Having described my invention what I claim as new and wish to secure by Letters Patent is:

1. A mechanism for lithographing comprising a movable lithographic surface mounted on a fixed frame, a closed refrigerating system comprising a refrigerating mechanism connected to said frame and means for reducing the temperature of said lithographic surface substantially to the dew point of the surrounding atmosphere for condensing a film of atmospheric moisture thereon, the sole source of the condensed moisture comprising the atmosphere surrounding the surface, said means being mounted to move with said surface and forming the low pressure side of said refrigerating system.

2. A mechanism for lithographing comprising a movable lithographing surface mounted on a fixed frame, a closed refrigerating system comprising a refrigerating mechanism connected to said frame and cooling coils for substantially reducing the temperature of said surface to the dew point of the atmosphere surrounding the surface to produce a condensation of moisture thereon, the sole source of said condensed moisture comprising the atmosphere surrounding the surface, said coils being integrally movable with said lithographing surface and mounted closely adjacent thereto.

3. A mechanism for lithographing comprising a hollow plate cylinder having a lithographic plate mounted thereon, a closed refrigerating system comprising a refrigerating mechanism removably connected to said plate cylinder and cooling coils integrally movable with and mounted within said cylinder and closely adjacent to said lithographic plate, the said cooling coils forming the low pressure side of said refrigerating system for substantially reducing the temperature of said plate cylinder to the dew point of the atmosphere surrounding it, to produce a film of moisture on said lithographing plate, the sole source of said film of moisture comprising the atmosphere surrounding the plate.

4. A mechanism for lithographing comprising a hollow lithographic plate cylinder having a lithographic plate thereon and mounted on and rotatable with a shaft, a fixed frame for movably supporting said shaft, a closed refrigerating system comprising a refrigerating mechanism detachably connected to said frame, and a tubular refrigerating element forming the cooling side of said refrigerating system for substantially reducing the temperature of said plate cylinder to the dew point of the atmosphere surrounding the plate to produce a film of moisture on the external surface of said lithographic plate, the sole source of said film of moisture comprising the atmosphere surrounding the plate and the said refrigerating element mounted closely adjacent the

inner surface of said plate cylinder and integrally movable with said plate cylinder and shaft.

5. A mechanism for lithographing comprising a hollow cylindrical lithographic surface mounted on and rotatable with a shaft provided with inlet and outlet channels, a fixed frame for supporting said shaft, a closed refrigerating system comprising a refrigerating mechanism detachably connected to said frame and means for substantially reducing the temperature of said surface to the dew point of the atmosphere surrounding it, to produce a film of moisture on said lithographic surface, said means consisting of a tubular cooling element having the ends thereof connected to ends of said inlet and outlet channels on said shaft, said tubular cooling element forming the low pressure side of the said refrigerating system.

6. A mechanism for lithographing comprising a hollow cylindrical lithographic surface mounted on and rotatable with a shaft having independent inlet and outlet channels therein, a fixed frame for rotatably supporting said shaft, a closed refrigerating system including a stuffing box and cap detachably connected to said frame, means for substantially reducing the temperature of said surface to the dew point of the atmosphere surrounding it, to produce a film of moisture on the external surface thereof, said means comprising a cooling coil circumferentially mounted within said lithographic surface to rotate therewith and having the ends thereof connected to the inner ends of the said inlet and outlet channels in said shaft the said cooling coil forming the low pressure side of said refrigerating system, and clamping means for supporting said cooling coil.

7. In a planographic printing-press including a revolute cylinder adapted to have the printing-plate mounted thereon, the combination with said cylinder of conduit means in and rotatable with said cylinder and forming the low-pressure gas-expansion portion of a cooling system, the complementary relatively-stationary high-pressure compression portion of said system external to said cylinder, and means operatively connecting said two portions together, said cooling system being adapted to reduce the temperature of the plate sufficiently to cause a deposit of dew on the plate from moisture-laden adjacent air.

8. In a planographic printing press including a revolute cylinder adapted to have the printing-plate mounted thereon, the combination with said cylinder of conduit means in and rotatable with said cylinder and forming the low-pressure gas-expansion portion of a cooling system, the complementary relatively-stationary high-pressure compression portion of said system external to said cylinder, and means operatively connecting said two portions together extending through one end only of said cylinder, said cooling system being adapted to cool said plate sufficiently to cause a deposit of dew on the plate from moisture-laden adjacent air.

JOHN G. GOEDIKE.
